UNITED STATES PATENT OFFICE

WALTER E. HASKIN, OF FLUSHING, NEW YORK, ASSIGNOR TO PRESSED & WELDED STEEL PRODUCTS CO., OF LONG ISLAND CITY, NEW YORK, A CORPORATION OF NEW YORK

BOOKSTAND

Application filed April 6, 1928. Serial No. 267,907.

This invention relates to bookstands and more specifically to a stand for supporting and permitting the manipulation of a reference book or books.

5 My invention is particularly adapted for use in connection with relatively heavy books and includes counterbalancing mechanism which aids in swinging the book from its closed position to its open position and prevents the too rapid return of the book to closed position.

An object therefore of the invention is to provide a bookstand of such character in which the book is counterbalanced so that a relatively heavy book can, through but a slight effort, be moved from its closed to open position, and returned to its closed position without shock or jar.

With these and other objects in view, the invention consists in certain novel features of construction and combinations and arrangements of parts, which will be more fully hereinafter described and pointed out in the claims.

20 In the accompanying drawings—

Figure 1 is a perspective view of my improved bookstand, showing the book in its closed position;

Figure 2 is a similar view, showing the book in open position;

Figure 3 is a view in vertical longitudinal section through one of the hollow standards of the bookstand, the view being taken on the line 3—3 of Figure 1;

Figure 4 is a view in transverse section of the bookstand, the view being taken on the line 4—4 of Figure 3;

Figure 5 is a view in section on the line 5—5 of Figure 4;

Figure 6 is an enlarged view in longitudinal section through my improved dash pot;

Figure 7 is a fragmentary view in transverse section illustrating a modification showing how a plurality of books may be supported by my improved stand;

Figure 8 is a view in section, similar to Figure 3, showing the book turned 90° on its pivot;

Figure 9 is a view, similar to Figures 3 and 8, showing the book turned 180° on its pivot.

In the accompanying drawings, I employ reference character A to indicate the bookstand as a whole, and I employ the reference character B to indicate the book, and the reference character C to indicate a backing 55 or binder to which the book is directly connected and supported thereby.

The bookstand A may of course be designed in many different ways but I have illustrated a simple form of bookstand in 60 which a pair of spaced parallel hollow box-like uprights 1, 1 is secured on the base 2, and is preferably connected at the back of the stand by a plate 3. These uprights 1, 1 may be of sheet metal with the parts formed and assembled in any approved manner and spaced apart sufficiently to accommodate the book B and book holder C between them.

The book holder C may also constitute a hollow member having any suitable arrangement of bars 4 located between the leaves of the book so as to secure the book to the backing, but it is to be distinctly understood that I do not wish to be limited to the specific construction of book support per se as this is 75 capable of modification. For books bound with hard covers the holder C, as shown in the drawings, is sufficient but for books or papers bound without hard covers the holder C should be otherwise made.

80 5 represents a shaft which extends through aligned openings or bearings in the inner walls of both standards 1, 1 and through the backing C so as to provide pivotal support and mounting for the backing and the book, and it will be noted particularly by reference to Figure 5 that this pivotal connection is nearer one end of the backing than the other so that it is slightly off center in relation to the book, so that the book will maintain itself 90 in closed position by gravity and will normally bear against a cushioning block 6 fixed to the backplate 3. It is to be understood that the backing C is secured or has a fixed relation to the shaft 5 and that the shaft 95 turns in bearings in the standards 1.

Crank arms 7 are fixed to the shaft 5 in both of the hollow standards 1, and the free ends of these crank arms 7 have crank pins 8 thereon to which chains or other flex- 100

ible connecting devices 9 are secured. These chains 9 are passed around idle pulleys 10 mounted in brackets 11 in the standards 1, and said chains are connected to the ends of 5 expansion springs 12, the other ends of said expansion springs being connected to fixed parts 13 of the standards, preferably through the medium of links 14, having turnbuckles 15 therein for adjustment of the tension of the springs. For a single volume one crank 10 arm 7 may suffice. It is not necessary to use two unless the book is so heavy as to make it desirable to use two springs. A spring and dash pot are required for each volume to act independently where more than one volume 15 is installed in the stand.

In one of the standards 1, I locate a dash pot 16 pivotally mounted at its lower end, as shown at 17, and the plunger or piston 18 of the dash pot 16 is connected by a bail 19, the walls of the dash pot casing being slotted, as shown at 20, to permit of this connection of the piston and bail.

The bail 19 is connected by a screw 21 with 25 a link 22, the latter connected to the crank pin 8 of one of the crank arms 7, the screw 21 permitting of the desired adjustment of the parts for proper functioning. The dashpot piston or plunger 18 has an air passage 23 therein with a check valve 24 in said passage so as to permit the flow of air in one direction through the passage and prevent the flow of air in the opposite direction.

In the modification illustrated in Figure 35 7 I show how a plurality of books B may be mounted in a bookstand A, and in this modification it will be noted that a sectional shaft 25 is employed, each section of the shaft supporting a book backing C and each shaft having the same arrangement of counterbalancing means as above explained in connection with the single book support, and like reference characters are employed to indicate like parts in the drawings.

The bookstand A is preferably provided 45 at the back thereof with a cushioning ledge or support 26 on which the backing C rests when the book is open, so as to aline the book with the upper surfaces of the standards 1 and allow the book to be opened and lie flat, as indicated in Figure 2 of the drawings.

The operation is as follows:

Figures 1, 3, 4 and 5 illustrate the position 55 of the parts when the book is in its closed position. When in this position it will be noted particularly by reference to Figures 3 and 4 that the crank arms 7 extend toward the rear and are in substantially horizontal position and the chains 9 are located (with relation to their connections to the arms) so that any strain of the springs is above the center of the shaft 5 so as to maintain the book in closed position.

To open the book, the outer or front end of the book illustrated in Figure 1 is elevated or

the opposite end of the book is pushed downwardly. This causes the arm 7 to swing downwardly and to the left of Figure 3 aided by the spring 12 as the latter contracts. Hence after the initial movement of the book 70 the spring 12 will exert power to turn the shaft 5 by reason of the leverage on the crank arm 7, so that the weight of the book is largely sustained by the spring and said spring 75 renders the turning of the book on its pivot an easy one, and the book can be easily swung from closed position to open position, the latter position being shown in Figure 2.

During this opening movement of the book, the piston 18 of the dashpot 16 is moved 80 downwardly and this action is relatively free as the check valve 24 will permit the air to pass through passage 23 in piston 18. When the book has been turned 90° to the position as shown in Figure 8, the piston 18 will be in its lowest position in the dashpot 16. When the book has been turned 180° on its pivot to the position as shown in Figures 2 and 9, the piston 18 will be in its highest position in the dashpot 16, the book holder C will be supported by its pivot and the cushioning ledge 26. The book when open will be supported by the holder C and the upper surfaces of the standards 1, and, while in this position, the leaves of the book can be conveniently 95 turned.

Figure 3 shows the book in the closed position. The dashpot is full-closed, all compressed air expelled and the spring expanded to the maximum. The chain is over dead center, and exerts a tendency to keep the book closed. The book however would normally remain closed by gravity by reason of the pivot point being off center. The leverage in this position is practically nil. The book being substantially in balance on its pivot pin very little effort is required to start the 100 operation of opening.

As the operation progresses the leverage 105 comes into play gradually. The spring tension being at its maximum in the closed position diminishes in substantially direct proportion to the increase in leverage, and the leverage increases in proportion to the increase in the resistance or weight of the book 110 as its turns on its pivot. When the book has been turned through an arc of 90°, as shown in Figure 8, its weight is at its maximum (that is, without any self-balancing influence over or under its pivot). Now the leverage of crank arm 7 is approaching its maximum whereas the spring tension is half diminished. The dashpot is full-open and up to this point has offered no resistance to the movement of the book by reason of the valve 115 24.

As the operation proceeds, the leverage still 120 further increases as the spring tension diminishes. The dashpot compresses the contained air by reason of the closing of the valve 24. 125

Approaching the full-open position of the book, the leverage passes its maximum and diminishes thereafter. Here again the force of gravity comes into play by reason of the 5 pivot point being off center and the heavy end of the book carries it through to the completion of the operation against the resistance of the dashpot only until the back strikes cushioning ledge 26 and the leaves fall open 10 by force of gravity and lock the book in an open position for reading.

Figure 9 shows the book turned through an arc of 180° with the dashpot again at full-closed position with its compressed air expelled. The spring tension has entirely faded out and the leverage is nil, as no force is necessary to keep the book open, and consequently no spring resistance is offered to the first movement of closing the book.

20 It is to be pointed out that the dashpot acts only to retard the too rapid opening or closing of the book to prevent jar or damage to the book on its support. It provides an air cushion only at the finish of the operation of opening or closing the book. It is so designed as to confine and compress the contained air, thereby creating a momentary air cushion or check only if the movement of the book is abnormally rapid. If the book 25 is handled at normal speed the dashpot offers only mild resistance to the movement.

The turnbuckle is provided to adjust the tension on the spring according to the weight of the book. It is desirable to have the 25 spring tension adjusted so that the book as shown in Figure 8 will automatically close by force of gravity instead of remaining in that position by reason of too much spring tension.

40 It is also to be pointed out that whereas the present case shows the book in a horizontal position, I do not wish to be limited to this position.

To return the book to closed position it is 45 necessary to first close the book itself and then move the book on its pivot and this movement is resisted by the springs 12, and if the book should be dropped or allowed to fall of its own weight the dashpot 16 will 50 function to check this closing or swinging movement of the book.

As above stated, the pivot of the book is slightly off center so that the book will of 55 its own weight remain either in open or closed position and require some slight manual effort to move it, although this effort is very slight as the weight of the book is counterbalanced by the action of the springs.

60 It is of course to be understood that my invention is broad enough to contemplate the counterbalancing elements equivalent to springs and other features, and while I have illustrated and described what I believe to be a preferred embodiment of my invention 65 it is obvious that various changes and alter-

ations might be made in the general form of the parts described without departing from my invention and hence I do not limit myself to the precise details set forth but consider myself at liberty to make such changes and alterations as fairly fall within the 70 spirit and scope of the appended claims.

I claim:

1. In combination with a bookstand, a book holder pivotally mounted between its ends and normally suspended in the stand and adapted to be moved from a closed position in the stand to an open position on the stand, and counterbalancing means operatively connected with the pivot of the bookholder, said pivot of the bookholder being nearer one end of the bookholder than the other whereby a book when contained in said holder will remain at rest by gravity in either its open or closed position. 75

2. A bookstand, including a base, hollow standards on the base spaced apart, a book holder located between the standards and adapted to contain a book, or the like, a shaft extending through the holder and into the standards, a crank arm on the shaft, an idle pulley in a standard, a coiled spring secured at one end in the standard, and a flexible device connecting the other end of the spring with the free end of the crank 90 arm and extending over said idle pulley. 95

3. A bookstand, including a base, hollow standards on the base spaced apart, a book holder located between the standards and adapted to contain a book, or the like, a shaft 100 extending through the holder and into the standards, a crank arm on the shaft, an idle pulley in a standard, a coiled spring secured at one end in the standard, a flexible device connecting the other end of the spring with 105 the free end of the crank arm and extending over said idle pulley, and a dashpot operatively connected to said crank arm.

4. A bookstand, including a base, hollow standards in the base spaced apart, a book 110 holder located between the standards and adapted to contain a book or the like, a shaft extending through the holder and into the standard, a crank arm on the shaft, an idle pulley in a standard, a coiled spring secured 115 at one end in the standard, a flexible device connecting the other end of the spring with the free end of the crank arm and extending over said idle pulley, a dashpot operatively connected to said crank arm, said dashpot having a piston therein, and a check valve controlled passage through the piston. 120

5. In a bookstand, the combination with a pair of spaced supports of a book holder pivotally connected between its ends to the supports with the exposed back of the book holder normally lying substantially flush with the upper ends of the supports, and counterbalancing means connecting the book holder and the bookstand assisting the pivotal movement 130

of the book holder to move the book to open position.

6. In a bookstand, the combination with a pair of spaced supports of a book holder pivotally connected between its ends to the supports, counterbalancing means connecting the book holder and the bookstand assisting the pivotal movement of the book holder to move the book to open position, and a dashpot connecting the book holder and the bookstand, operating to check the fall of the book holder.

7. In a bookstand, the combination with a pair of supports of a book holder pivotally connected intermediate its ends to the supports and normally lying substantially flush with the upper ends of the supports, a transverse member on the bookstand, said pivotal connection being nearer one end of the book holder than the other whereby when the book holder is swung from its closed position to its open position one end of the book holder will rest on said transverse member and counterbalancing means connecting the book holder and book stand assisting the pivotal movement of the book holder.

25 8. In a bookstand, the combination with a pair of spaced upright supports, of a book holder located between the supports and pivotally connected intermediate its ends to the supports, and a dashpot operatively connected to the book holder and checking the falling movement of the book holder as it is swung from one position to another.

35 9. An apparatus of the character described adapted to pivotally support, counterbalance the weight and check the fall of a book holder and a book, said apparatus including a support in which the book holder is pivotally mounted between its ends, resilient means 40 connecting the book holder and the support, assisting the operator to pivot the holder, and a dashpot connecting the book holder and the support and checking the fall of the book holder after it swings through a predetermined arc.

45 Signed at Long Island City in the county of Queens and State of New York this 4th day of April A. D. 1928.

WALTER E. HASKIN.
